SPRING STRUCTURE

Nathan C. Goldberg, New York, N. Y.

Application February 14, 1942, Serial No. 430,913

5 Claims. (Cl. 5—267)

The present invention relates to spring structures such as are used in beds, couches, hammocks and the like and especially to that type of spring structure wherein a series of upright coil springs are arranged in parallel rows and columns in the space between upper and lower frames or frame pieces and are held in proper spaced relation within the area surrounded by the said frames.

The principal object of the present invention is to provide a spring structure of the aforementioned type or kind which is sturdy in construction and durable in use and in which the coil springs are so assembled and held in proper spaced relation as to secure the optimum amount of flexibility and yieldability.

Another object of the present invention is to provide a spring structure of the aforementioned type and character, in which the numerous coil springs are so assembled and held in proper place and relation, as to divide the spring structure into a plurality of independently yieldable portions or areas each of which is adapted to yield to the load placed thereon without causing undue tension and strain upon any other portion of the spring structure.

Other objects and advantages of the present invention will become apparent as the description of the illustrative embodiments of the invention proceeds.

With the above and other objects in view the invention consists of the novel features of construction, combination of elements and arrangement of parts hereinafter described and illustrated in the accompanying drawings.

In the accompanying drawings which form an integral part of this specification;

Fig. 1 is a top plan view of a fragmentary portion of a spring structure in which the present invention has been embodied;

Fig. 2 is a top plan view of an enlarged scale of a fragmentary portion of the spring structure shown in Fig. 1;

Fig. 3 is a vertical sectional view taken on the line 3—3 of Fig. 2;

Fig. 4 is a top plan view of a fragmentary portion of a spring structure in which a modified form of the present invention has been embodied;

Fig. 5 is a top plan view on an enlarged scale of a fragmentary portion of a spring structure in which a still further modified form of the present invention has been embodied.

Referring now to the drawings wherein like reference characters indicate corresponding parts throughout the several views, the spring struc-

ture shown in Figs. 1, 2 and 3 consists essentially of a series of upright coil springs 10 (shown diagrammatically in Fig. 1) arranged in spaced longitudinal parallel rows throughout an area 5 surrounded by a frame comprising a rigid upper frame piece 11 and a rigid lower frame piece 12 spaced apart vertically. The lower frame piece 12 is provided with a plurality of spaced parallel rigid longitudinal frame bars 13 having their opposite ends welded or otherwise suitably secured to the adjacent ends of said frame piece. Each of the rigid members 13 serves to support one of the parallel rows of coil springs 10 and for effecting such support each member 13 is provided at spaced intervals along its length with pairs of openings 14, each pair being adapted for threading the lower convolution of one of the coil springs 10 therethrough, thus affording a firm and simple base for each coil spring. The 10 marginal coil springs of the series of springs have their upper convolutions securely anchored to the upper frame piece 11 as by the studs 15, along the two sides and the two ends of the frame. In referring to the members 11, 12 and 13 as 15 rigid, it is intended to indicate that they are substantially rigid or relatively rigid as compared with the spring elements contained within the outline of the entire spring structure.

In accordance with the present invention there 20 is provided a plurality of sets of parallel cables, designated generally by the letter C, which extend longitudinally between the rows of coil springs in parallel relation thereto. Each of the sets of cables is composed of several sections in tandem, 25 preferably in the form of groups of elongated stranded wire loops 16 which are connected in alignment by helical springs 17, the loops and springs together forming a yieldable and extensible cable structure. Although any desired number 30 of aligned groups of cable loops may be employed to constitute one set of cables, two or four groups of loops are considered most suitable to carry into effect the purposes of the present invention. When the cable is composed of two 35 groups of loops the connecting helical springs 17 are located at the midpoint of the cable, and when four groups of loops constitute the cable two additional groups of helical springs are 40 preferably located towards the ends of the cable. The end loops of the cables are shown in Figs. 45 1 to 4 as anchored directly to the adjacent ends of the upper frame 11 as by the studs 18. It may be desirable, however, to effect the anchorage by means of intervening tension springs, not 50 shown.

In order to tie the cable sets C to the coil springs 10, there is provided in accordance with the present invention, a plurality or system of connecting devices shown as consisting of successive portions of flat metal bands 19 which extend transversely between the columns of coil springs at an angle to the rows, preferably at right angles, as shown in Figs. 1 to 5. Each of the bands is provided with a series of such portions or connecting means, for example, by struck tongues or offsets 20, shown in Fig. 2, which form sets of parallel passages at spaced intervals along the length of the band, each set of passages at the nodes or connector points of the several bands being adapted to receive a set of cable lengths or loops 16, each of which is threaded or traverses reentrantly through a pair of parallel passages of one or more bands. Each band is yieldably connected to all of the adjacent coil springs by helical springs 21, four of which connect each nodal or connector region of the band, defined by the offsets 20, respectively to the upper convolutions of the four adjacent coil springs.

In the modified form of spring structure illustrated in Fig. 4, the construction is similar to that of the spring structure above described and illustrated in Figs. 1, 2 and 3, except with respect to the connecting devices for tying the sets of cables to the coil springs. Instead of the unitary band structure provided in the foregoing embodiment of my invention, each of the transverse connecting means consists of several flat metal band sections 22 which are connected in mutual alignment by helical springs 23, forming therewith a yieldable and extensible band structure extending at right angles to all of the parallel sets of cables. Each of the band sections preferably spans several groups of parallel cable loops 16 and, as in the case of the connecting devices described with reference to Fig. 1, each of the band sections is provided at its connecting or nodal portions with offsets or tongues 20 which form sets of parallel passages adapted for receiving and accommodating the strands of the cable loops therethrough.

In the modified form of spring structure shown in Fig. 5, the construction is similar to that of the spring structure shown in Figs. 1, 2 and 3, with or without the modification of Fig. 4, but instead of the sets of cables C being extended clear to the ends of the upper frame piece 11 and anchored thereto by the studs 18, as shown in Figs. 1 to 4, the cables terminate at the outermost or marginal bands 19 and are retained thereat by the retaining clips or offsets 20 around which the ends of the cables are looped.

From the foregoing description of the several embodiments of my invention it will be observed that by the provision, between the rows of coil springs, of longitudinal cable sets each composed of several sections connected in alignment by resilient springs, the spring structure as a whole is divided into several longitudinal sections or panels each of which will yield to the load placed thereon without unduly tensioning and straining any other section. This is a decided advantage over former spring structures in that a person lying longitudinally on one side or portion of a bed in which the spring structure of the present invention is used may shift without causing discomfort to a person lying on another portion of the same bed. It will also be observed that by the provision of the sectional bands transversely of the longitudinal rows of springs, the spring structure is further divided into several inde-

pendently yieldable transverse sections, thereby providing a spring structure of an even greater extent of adaptability and yieldability.

Other advantages of the present invention will be obvious to those skilled in the art to which the present invention relates.

For example, it may be found to be desirable to connect the sections of the successive sets of cables which extend across the upper frame from end to end by incorporating yieldable connections or helicals extending substantially in a line transversely of the cables, and which line is approximately midway of the opposite longitudinal sides of said frame. Hence the invention is not restricted except as defined in the appended claims.

I claim:

1. A spring structure of the character described comprising in combination, a system of upright coil springs arranged in longitudinal parallel rows, relatively rigid upper and lower frame pieces surrounding said system of coil springs, the lower of said frame pieces having means for supporting the coil springs, and the tops of the coil springs adjacent to the upper frame piece being anchored thereto, a plurality of sets of longitudinal cables extending between said rows of coil springs in parallel relation thereto, each of said cable sets comprising separate parallel cables and each set being subdivided into a plurality of sections in spaced alignment, with tension springs interconnecting the spaced adjacent ends of such sections, a plurality of connecting devices each comprising a metal element formed with a plurality of parallel passages accommodating therein the separate cables of a set of said cables, and tension means for yieldably connecting each of said connecting devices respectively to the tops of all of the adjacent coil springs, the outermost of the connecting devices nearest the opposite ends of the upper frame piece having the outermost ends of the cable sets secured thereto, thereby allowing relatively yieldable up or down movement of said outermost cable set ends and connecting devices.

2. A spring structure of the kind described having surrounding under and upper frame members and a system of upright coil springs arranged in longitudinal rows and transverse columns, with underneath support from the under frame member, and the outermost coil springs endwise and sidewise having their tops laterally anchored to the upper frame member, in combination with a series of grouped sets of parallel cables extending longitudinally between the coil spring rows but terminating short of the frame ends, and a series of parallel metal bands extending transversely between the coil spring columns and crossing such cable-sets but terminating short of the frame sides, successive length portions of each such band being formed with a set of passages in which the separate cables of each set are engaged, the ends of each cable-set being secured to the two outermost of such longitudinal bands, and tension springs extending from such successive band portions to the tops of the adjacent coil springs thereby to tie the transverse bands and the longitudinal cable-sets to the coil spring tops.

3. A spring structure as in claim 2 and wherein each cable set is sectional, with its sections in tandem alignment and interconnected by tension springs.

4. A spring structure of the character described comprising in combination, a system of upright coil springs arranged in longitudinal parallel rows, relatively rigid upper and lower frame pieces

surrounding said system of coil springs, the lower of said frame pieces having means for supporting the coil springs, and the tops of the coil springs adjacent to the upper frame piece being anchored thereto, a plurality of sets of longitudinal cables extending between said rows of coil springs in parallel relation thereto, each of said cable sets comprising separate parallel cables, a plurality of connecting devices each comprising a metal element formed with a plurality of parallel passages accommodating therein the separate cables of a set of said cables, and tension means for yieldably connecting each of said connecting devices respectively to the tops of all of the adjacent coil springs, the outermost of the connecting devices nearest the opposite ends of the upper frame piece having the outermost ends of the cable sets secured thereto, thereby allowing relatively yieldable up or down movement of said outermost cable set ends and connecting devices.

5. A spring structure of the kind described having surrounding under and upper frame members and a system of upright coil springs arranged in

longitudinal rows and transverse columns, with underneath support from the under frame member, and the outermost coil springs endwise and sidewise having their tops laterally anchored to the upper frame member, in combination with a series of grouped sets of parallel cables extending longitudinally between the coil spring rows in parallel relation thereto, and each cable set being subdivided into a plurality of sections in spaced alinement, with tension springs interconnecting the spaced adjacent ends of such sections, and a series of parallel metal bands extending transversely between the coil spring columns and crossing such cable-sets but terminating short of the frame sides, successive length portions of each such band being formed with a set of passages in which the separate cables of each set are engaged, and tension springs extending from such successive band portions to the tops of the adjacent coil springs thereby to tie the transverse bands and the longitudinal cable-sets to the coil spring tops.

NATHAN C. GOLDBERG.
